CLAIM

The ornamental design for a lift for utility vehicle, as shown and described.

DESCRIPTION

FIG. 1 is a perspective view of the lift for utility vehicle;
FIG. 2 is a front view of the lift for utility vehicle;
FIG. 3 is a first side view of the lift for utility vehicle;
FIG. 4 is a top view of the lift for utility vehicle;
FIG. 5 is a rear view of the lift for utility vehicle;
FIG. 6 is a second side view of the lift for utility vehicle; and,
FIG. 7 is a bottom view of the lift for utility vehicle.
The broken lines showing in FIGS. 1-7 are included for the
purpose of illustrating portions of the lift for utility vehicle
that form no part of the claimed design.
